UNITED STATES PATENT OFFICE.

JOHN T. WHITEHOUSE, OF CLEVELAND, OHIO, ASSIGNOR TO THE VAN DORN IRON WORKS COMPANY, OF CLEVELAND, OHIO, A CORPORATION OF OHIO.

DEADLOCK FOR JAIL DOORS.

Application filed April 9, 1927. Serial No. 182,369.

This invention relates to the locks of doors for jails or other like institutions, its object being to provide an improved lock which is sturdy, strong and well able to withstand efforts of destruction, which is of simple construction, capable of production at low cost and of simple operation, and in which the mechanism is of simple form and unlikely to get out of order, and, further, a lock of this kind provided with simple and efficient means for protecting it not only against picking or attempts to open the lock by an unauthorized person, but which also prevents the turnkey or other authorized person from damaging their locks or keys by inadvertently attempting to open a lock with the wrong key, all as will more fully appear, together with other advantages more apparent to those skilled in the art.

In the drawings which represent one suitable embodiment of the invention, Fig. 1 is a front elevation with a part of the casing cover broken out to expose interior parts; Fig. 2 is a sectional plan view on the line 2—2, Fig. 1; Fig. 3 is a detail sectional plan view, corresponding to Fig. 2, and showing the lock cover and its special wards; Fig. 4 is a vertical section along the line 4—4, Fig. 3; Fig. 5 is a front elevation, corresponding to Fig. 1 and showing the lock hub; and Fig. 6 is a detail view of a key suitable for actuating the lock.

The lock casing is of simple form suitable for insertion and securement in a recess of the door. It comprises a hollow body portion 1 and a cover plate 2 secured thereto by screws 3, the body having openings 4 for attaching the lock to the door. In the cavity of the lock, and operating through an opening in one end thereof is a bolt 5 which may be protected against sawing operations by the pins 6 of tool resisting metal cast therein. The central portion of the bolt is hollowed out or open, providing two parallel arms 7 with a space between them and the rear bridge 8 connecting them. As shown in Fig. 2 that portion of the bolt lying within the casing is of reduced thickness to provide space for the lock tumblers, and this portion 50 of the bolt has attached thereto a lateral projection 9 adapted to pass back and forth through gates or openings in a series, four being shown, of swinging tumblers 10, said gates, marked 11 leading to back recesses 12. The tumblers are mounted to swing on a suit-

able post, such as a pin 13 cast integral with the casing body 1 and, indeed, the casing body and cover may be made as die castings to reduce the cost. Each two adjacent tumblers are separated by spacing washers 14 and each thereof at about the center of the lock is provided with a recess or through opening 15 through which the key passes, and the upper edges 15^a of all of which openings are engaged by the wards of the key to move the tumblers to proper position to enable the projection 9 to move back and forth through the gates 11 as the bolt is moved. Obviously the several wards of the key will vary in height and the gates 11 on different tumblers will be located at varying distances between their side edges to require special positioning of each tumbler for actuation of the lock. The tumblers may operate by gravity when the lock lies in the position shown in Fig. 1, but to avoid mischance, as by one tumbler sticking, and to enable the lock to be used in other positions, I also provide each tumbler with suitable means such as the spring 16 to normally move it to the position shown in Fig. 1.

Coaxial with the key opening in cover 2 and rotatable in the boss of the casing body 1 is a lock hub 17 shown in detail in Fig. 4 and provided with a central opening through which the key extends, and two inward projections or teeth 18 into said opening, and on its periphery with teeth 19 engaging rack teeth 20 on the lock bolt. Rotation of the lock hub by the key moves the bolt back and forth, as will be readily understood.

Referring to Fig. 1, the key is inserted with its wards extending horizontally and therefore lying adjacent to the projections 18 of the lock hub. To retract the bolt the key is turned counter clockwise and it rotates for about 150 degrees without producing movement of the lock hub. Finally its wards engage the projections 18 at the same time that its wards have moved the tumblers to bolt release position, whereupon continued counter clockwise key rotation turns the hub and retracts the bolt, its projection 9 passing through the gates 11 and entering the recesses 12. Continuation of 180 degree key movement permits the tumblers to return to bolt locking position, with the bolt locked retracts. The reverse operation is similar and requires no description.

The keys to locks of this kind are cus-

tomarily not marked or identified, to prevent prisoners from acquiring from the key any information of what lock it controls. As a result the turnkey or other authorized person occasionally attempts to unlock a lock with other than the correct key to the consequent damage to either key or lock. Moreover, these keys must be so made as to enable the lock to be actuated from either side. Accordingly the present invention provides the lock with special wards which prevent actuation or attempted actuation in any lock of other than the proper key, but nevertheless allows for proper symmetry of the key for actuation of the lock from either side. As shown in Figs. 2 and 3, one of the parts of the lock casing such as the cover is provided with an inwardly extending boss 24 of semi-circular form when viewed in elevation, and the inner surface of which is turned out to provide a series of wards 21 for cooperation with the key and designed to prevent any but the proper key from being worked in the lock. One suitable key for the lock is shown in Fig. 5, comprising a shank 22 and wards which may be considered to be quartered into four members 23^a, 23^b, 23^c, and 23^d. Upon insertion of the key into the lock through the cover or from the bottom in Fig. 2 it will be obvious that the wards of member 23^d actuate the tumblers, the wards 23^c pass the wards 24 of the lock cover and the wards 23^a and 23^b engage the projections 18 and turn the lock fall. When the same key is inserted through the body 1 of the lock casing or from the top in Fig. 2, the wards 23^a and 23^b actuate the tumblers and pass the wards 24, while the wards 23^c and 23^d actuate the lock fall.

40 This lock is quite satisfactory for the purpose and not only protects the key against damage by the wrong lock, but also protects the lock against injury by the key.

What I claim is:

45 1. In a lock, a casing having a key receiving and supporting aperture, a bolt slidable in said casing, a plurality of tumblers in said casing adapted for movement therein to control said bolt movement and arranged for individual engagement by a corresponding plurality of wards of a key inserted through said aperture and turned to effect said movement, said casing having a boss adjacent said aperture, said boss having wards in the planes of the tumblers and adapted to prevent turning in said lock of a key inserted through said aperture and having ward portions symmetrical about the turning axis of the key and exceeding the necessary dimensions to properly actuate said tumblers.

50 2. In a lock, a casing having a key receiving and supporting aperture, a bolt slidable in said casing, a plurality of tumblers in said casing adapted for movement therein to control said bolt movement and having through

openings with ward portions arranged for individual engagement by a corresponding plurality of wards of a key inserted through said aperture into said tumbler openings and turned in said casing to effect said movement, a boss secured in said casing and extending within the openings of said tumblers, and said boss having wards in the planes of the tumbler wards and adapted to prevent turning in said lock of a key having ward portions symmetrical about the turning axis of the key and exceeding the necessary dimensions to properly actuate said tumblers. 75

3. In a lock, a casing having aligned key receiving and supporting apertures, a bolt slidable therein, a plurality of tumblers in said casing adapted for movement therein to control said bolt movement and having parallel recessed ward portions arranged for individual engagement by a corresponding plurality of wards of a key inserted through either of said apertures and extending into said recessed tumbler portions and turned in said casing to effect bolt movement, said casing having a boss extending within said recessed tumbler portions, and said boss having wards in the planes of the tumbler wards and adapted to prevent turning in said lock of a key having wards exceeding predetermined dimensions. 90

4. In a lock, a casing having aligned key receiving and supporting apertures, a bolt slidable in said casing, a hub having a bolt engaging portion and mounted for rotation in said casing coaxial with said apertures to slide said bolt, a plurality of tumblers in said casing adapted for movement therein to move said bolt and having recessed ward portions arranged for individual engagement by a corresponding plurality of wards of a key inserted in either of said apertures and extending into said tumbler recessed portions and turned in said casing to effect said movement, said hub having a portion adapted for engagement by a key ward portion after rotation of said key in said lock to effect said tumbler movement, a boss secured in said casing adjacent one of said apertures and extending within said tumbler recessed portions, said boss having wards in the planes of the tumbler wards and adapted to prevent turning in said lock of a key having wards exceeding predetermined dimensions. 105

5. In a lock, a casing having aligned key receiving and supporting apertures, a bolt slidable in said casing, a hub having a bolt engaging portion and mounted adjacent one of said apertures for rotation in said casing coaxial with said apertures to slide said bolt, a plurality of tumblers in said casing adapted for movement therein to clear said bolt and having recessed ward portions arranged for individual engagement by a corresponding plurality of wards of a key inserted in either of said apertures and turned in said casing to 110

effect said movement, said hub having portions adapted for engagement by another key ward portion after rotation of a key in said lock to effect said tumbler movement, a boss secured in said casing adjacent the other of said apertures and extending within said tumbler recessed portions and having wards in the planes of the tumbler wards and adapted to prevent turning in said lock of a key

having wards exceeding predetermined dimensions, said parts being arranged for operation as described by a key having its ward portion in a plane and symmetrical about two axes.

In testimony whereof I hereby affix my signature.

JOHN T. WHITEHOUSE.
